United States Patent Office.

WILLIAM H. WILEY, OF FREDONIA, NEW YORK.

Letters Patent No. 70,768, dated November 12, 1867.

IMPROVEMENT IN HORSE-POWER.

The Schedule referred to in these Letters Patent and making part of the same.

TO ALL WHOM IT MAY CONCERN:

Be it known that I, WILLIAM H. WILEY, of Fredonia, Chautauqua county, and State of New York, have invented a certain new and useful Improvement in Horse-Power; and I do hereby declare that the following is a full, clear, and exact description thereof, reference being had to the accompanying drawings, making a part of this specification, in which—

Figure I is a top plan view.

Figure II is a longitudinal vertical section.

Figure III is a cross-section on line X Y, Fig. I.

My invention relates to that class of horse-power machines in which the horses travel around a vertical axis, and give motion to a vertical shaft, by an arrangement of draught-poles and gearings.

In the use of horse-power machines, they are frequently required to produce reciprocating motions, as in operating wood-mills; and at other times continuous circular motion, as in operating threshing machines, feed-cutters, and other farm implements. The nature of my invention consists—

First. In extending the frame of the machine (by which the vertical shaft and driving-gearing are supported,) laterally across and beyond the circular road travelled by the horses, and providing said frame extension, first, with slides for the reception of a drag-saw cross-head, so that said drag-saw may be operated directly from the central driving-shaft by a pitman connecting said cross-head with a crank on said driving-shaft; and secondly, in providing said frame extension with bed-pieces fitted for the reception of pillow-blocks, (when the drag-saw cross-head and pitman are removed,) to form bearings for the support of a horizontal shaft, receiving motion from the vertical shaft through the medium of a pair of bevel-gears, and carrying upon its outer end a pulley, from which motion may be transmitted to any of the before-mentioned machines; by which plan of construction and arrangement the machine is readily adapted to the production of either circular or reciprocating motion, and in either form all the parts are firmly supported by the same frame, and any disalignment thereof prevented.

Second. In providing for a change in velocity of the main driving-shaft under a uniform travel of the horses in feet per minute, by providing the rotating-table, to which the draught-poles are attached, with pinion-spindles, placed at varying distances from the axis of rotation of said table, so that pinions of varying sizes may be used between the stationary cog-rim and main-shaft pinion, to increase or diminish the velocity of the main shaft, as required.

Letters of like name and kind refer to like parts in each of the figures.

A represents the main frame of the machine, upon which the operating parts are supported, and A' represents a covered extension thereof, below which those parts are located which transmit the power to the outside of the circular road upon which the horses travel. B represents the main central driving-shaft, which is secured in appropriate bearings formed upon the main frame of the machine, and carries upon its top a pinion, b'. C represents a table, which revolves upon a chilled cast-iron spindle, C', through which the shaft B passes, and which is located immediately below the pinion b'.

Upon this table I securely bolt four or more vertical arms or spindles D, at unequal distances from the centre of table C, which form appropriate fulrora for the gearing hereinafter described. These spindles or arms are made of cast iron, chilled or hardened. This renders them capable of resisting any strain which may be put upon them, and prevents their wearing out in consequence of excessive friction. Each spindle has a bed-plate, which is securely bolted to the table C, and each is made hollow, so that a bolt may be passed vertically through the same, for connecting the table to the draught-poles or levers E. There may be four or more arms or poles, which are connected in the centre by means of the strengthening bracket e'. The bolts which pass through the arms or spindles D reach up through the poles, and have a nut upon their upper end, by which means the poles or levers may be attached to and detached from the table with great convenience and little loss of time.

F represents a circular internal gear, which is securely bolted to the top of the main frame A. G G' represent spur-wheels, having pinions attached upon their under side, which are placed upon two of the spindles

D in such manner that the pinion will mesh with the internal gear F, and the spur-wheel with the pinion b' upon the central shaft B; and hence, when the table C is revolved by means of the levers E, the pinion b' and shaft B will be revolved with an increased velocity, proportionate to the difference in the diameter of the intermediate spur-wheels and pinions G.

In order to be able to produce a greater velocity of movement of the central shaft B with the same velocity of the levers or prime movers, I provide an additional set of spur-wheels and pinions, the difference in the diameters of which is greater than that of the spur-wheels and pinions G G'. The varying distance of the spindles D from the centre of the table C corresponds with the difference in size of the pinions, so that they will all properly mesh with the cog-rim. This additional set of gearing is shown in red dotted lines, fig. 1, in the position the same occupies when used in lieu of the gearing G G'. It will be readily seen that where great strength is not an object, only one spur-wheel and pinion of either set of gearing may be used to advantage; but for heavy work both should be used.

H H are boss-pinions, which are placed upon two of the spindles D, between the driving-gear. They mesh with the internal gear F, and serve to strengthen and steady the movement of the levers and table. These boss-pinions may or may not be used, as desired, but when only one spur-wheel and pinion G should be employed, one of these boss-pinions must always be placed upon the spindle opposite the gearing, for the purpose of preventing undue strain upon all the operating parts.

I represents a horizontal shaft, supported in bearings upon the adjustable cross-pieces i¹ i², which are parts of the extension of the frame of the machine A'. Upon its outer end this shaft carries an overhung pulley, J, for which (by means of a belt) power may be transmitted to any one of the various agricultural machines now in use, such as feed-cutters, threshing machines, and the like. Upon the opposite or inner end a bevel-wheel, K, is attached, which gears with a corresponding bevel-wheel, L, upon the lower end of the vertical shaft B. This bevel-wheel L is so constructed that it may also be used as a crank, a projection being formed upon one side thereof for that purpose. By this means the power of the machine may be applied to and changed into a wood-mill by a simple and easy change in the connections. The cross-pieces i¹ i² are taken off by unscrewing a bolt or bolts upon their upper side, and the horizontal shaft I, bevel-wheel K, and pulley J lifted out of the frame and removed. Then the cross-head m is placed within the slides m', which are a fixture upon the framework, and a connection between the cross-head and crank L is formed by means of the pitman n. The cross-head m and pitman n are both shown in red dotted lines, representing them to be used in lieu of the horizontal shaft I, bevel-wheel K, and pulley J. A drag-saw may be attached to the cross-head m in a common manner, and the wood-mill is complete.

The changes necessary to increase or diminish the speed of the driving-shaft may be made easily and in a short time, as may also the changes necessary to produce reciprocating motion, or circular motion, when required.

Both of these features meet a long-felt want of farmers, by whom these machines are principally used. The first enables them to suit the speed to the power and strength of their horses, and the second removes a great difficulty, existing in other machines, in the setting up and arrangement thereof for the several kinds of work to be done.

Having thus described my invention, what I claim, and desire to secure by Letters Patent, is—

1. Extending the frame of the machine laterally across and beyond the circular track travelled by the horses, and providing the same with slides for the reception of a drag-saw cross-head, and with bed-pieces for the horizontal shaft pillow-blocks, in the manner and for the purposes described.

2. Securing the pinion-spindles D to the table C, at varying distances from the centre thereof, so that different sizes of pinions, to gear with cog-rim F, and spur-wheels, to gear with pinion b', may be used, as and for the purpose set forth.

WILLIAM H. WILEY.
